(57) **CLAIM**

The ornamental design for a container and blank for forming same, as shown and described.

DESCRIPTION

FIG. 1 is a top plan view of a container and blank for forming the same showing our new design in its blank, unassembled condition, the bottom plan view being a mirror image thereto; FIG. 2 is an end elevation view thereof, the opposite end being identical thereto;

FIG. 3 is a side elevation view thereof, the opposite side being identical thereto;

FIG. 4 is a top perspective view of a container and blank for forming the same showing the fully assembled design;

FIG. 5 is an opposite top perspective view thereof;

FIG. 6 is a bottom perspective view thereof;

FIG. 7 is a top plan view thereof;

FIG. 8 is a bottom plan view thereof;

FIG. 9 is a side elevation view thereof, the other side being identical thereto; and,

FIG. 10 is an end elevation view thereof, the other end being identical thereto.

The dot-dash broken lines shown in FIG. 1 represent claimed fold lines.
